Specification for Design.

Patented Oct. 4, 1921.

Application filed June 27, 1921. Serial No. 480,937. Term of patent 14 years.

To all whom it may concern:

Be it known that I, BERNARD T. PENNIG, a citizen of the United States, residing at St. Paul, in the county of Ramsey and State of Minnesota, have invented a new, original, and ornamental Design for a Mail-Box, of which the following is a specification, reference being had to the accompanying drawing, forming a part thereof.

Fig. 2 is a rear view, in perspective, of the same.

I claim:

The ornamental design for a mail box, as shown.

BERNARD T. PENNIG.
